UNITED STATES PATENT OFFICE.

WILLIAM A. SMITH AND CLARENCE H. DOCKHAM, OF DETROIT, MICHIGAN, AS-SIGNORS TO CHICAGO PNEUMATIC TOOL COMPANY, OF NEW YORK, N. Y., A CORPORATION OF NEW JERSEY.

PNEUMATIC TOOL.

Application filed June 6, 1921. Serial No. 475,535.

To all whom it may concern:

Be it known that we, WILLIAM A. SMITH and CLARENCE H. DOCKHAM, both citizens of the United States of America, residing at Detroit, in the county of Wayne and State of Michigan, have invented certain new and useful Improvements in Pneumatic Tools, of which the following is a specification, reference being had therein to the accompanying drawings.

The invention relates to pneumatic tools and similar fluid-operated devices and consists in the novel construction of the controlling valve as hereinafter set forth.

15 In the drawings:

Figure 1 is a longitudinal section through a pneumatic tool of our improved construction, showing the piston at the start of its working stroke;

20 Figure 2 is a similar view with the piston at the start of its return stroke;

Figures 3 and 4 are views similar to Figures 1 and 2 showing a modified construction.

25 A is the cylinder, B is the piston therein and C is the controlling valve. This valve is of spool form, being provided with the end heads C' and C², a central disk C³ of greater diameter, and annular chambers C⁴ and C⁵ between said disk and heads. D is the housing for the valve having a cylindrical bore of sufficient diameter for the passage of the central disk C³, and E and E' are bushings within the casing which fit 30 the end heads C' and C² and which are spaced from each other to receive the central disk C³ and to provide an air passage adjacent thereto. The casing D has a main air passage F surrounding the inner ends of

35 the bushings and is further provided with channels G and H leading from chambers at opposite ends of the valve to opposite ends of the cylinder A. Between these end channels and the central air passage F are

40 channels I and J, which are in constant communication respectively with the chambers C⁴ and C⁵ in the valve and with the cylinder adjacent to opposite ends thereof. K is an annular main exhaust passage arranged centrally of the cylinder A and adapted to be 45 over-run by the piston B.

With the construction as described the central disk C³ is adapted to seat alternately upon the ends of the bushings E and E' and

when so seated, will cut off communication between the air supply passage F and one of the chambers C⁴ and C⁵ while establishing communication between said passage and the other of said chambers. The shifting of the valve is caused by the increase of pressure on one or the other of the end heads C', C², after the piston B has passed the main exhaust channel K and operates as a compressor. The central disk C³ being of greater diameter than the end heads, will expose a larger area of the fluid pressure, but this is reduced by tapering the ends of the bushings so as to restrict the width of the seat and to permit a balancing pressure on the portion of the valve outside of said seat.

With the modified construction shown in Figs. 3 and 4, a different means for shifting the valve is provided. This comprises a restricted passage L connecting the main air passage F with a chamber M at one end of the valve, which end is reduced in diameter as indicated at N. The opposite end of the valve, which is of larger diameter, is subjected to pressure in the chamber O connected by the passage P with the main air passage and by the passage Q with the cylinder at a point on one side of the main exhaust channel K. The arrangement is such that a constant pressure will act upon the end N of the valve, while the pressure on the opposite end is alternately exhausted and built up by the sealing or unsealing of the channel Q by the piston. When the channel Q is opened to the exhaust, the pressure upon the end N will shift the valve in one direction and as soon as the channel Q is sealed by the piston, the pressure in the chamber O will build up and the larger area exposed to this pressure will overcome the pressure on the end N, shifting the valve in the opposite direction. The valve also controls auxiliary exhaust passages R and S, which are controlled by the opposite end heads C' and C² and are alternately connected with the chambers C⁴ and C⁵.

With both of the constructions respectively illustrated in Figures 1, 2 and 3, 4, the center disk C³ will seat upon the ends of the bushings operating as a poppet valve, while the pressures upon the opposite ends of the valve are relatively varied to cause the shifting of the same. The amount of

movement required is less than with a piston type valve and the positive seating will prevent all leakage.

The complete cycle of operation in the construction as shown in Figures 1 and 2 is as follows: The piston and valve being in the positions shown in Figure 1, the compressed air is admitted from the supply passage F to the chamber C⁴ of the valve to the left of the central disk C³ and through the channel I to the left-hand end of the cylinder. This will drive the piston B forward to deliver a blow on a tool, the air in advance of the piston being exhausted through the channel K. After the piston has over-ridden the channel K, the drop in pressure occasioned by the exhausting of the air therethrough will be communicated through the channel G to the left-hand end of the valve and through the channel I to the chamber C⁴. At the same time the compression of the trapped air by the piston will raise the pressure which is communicated through the channel H to the right-hand end of the valve and through the channel J to the chamber C⁵, thereby effecting the shifting of said valve into the position shown in Figure 2. Compressed air will then be admitted from the supply passage F through the chamber C⁵ at the right of the central disk C³ and through the channel J to the cylinder to the right of the piston. This will drive the piston through its return stroke and after the exhaust channel K has been over-ridden, the exhausting of the pressure in the channels H and J, together with the compression of the trapped air which is in communication with the channels G and I, will again shift the valve into the position shown in Figure 1.

In Figures 3 and 4 the cycle of operation is as follows:—The piston and valve being in the position shown in Figure 3 the compressed air is admitted from the supply passage F through the restricted passage L to the chamber M subjecting the reduced end N to a continuous pressure and tending to force the same to the left. The compressed air is also admitted at the same time through the restricted passage P to the chamber O which communicates with the main exhaust channel K when the piston is in the position shown in Figure 3. The main compressed air supply, however, is admitted from the passage F to the right of the central disk C³ when the valve is positioned, as shown in Figure 3, and through the enlarged passage to the right hand end of the cylinder. This will drive the piston B forward to deliver the blow on the tool the air in advance of the piston being exhausted through the channel K. After the piston has over-ridden the channel K the drop in pressure occasioned by the exhausting of the air therethrough will be communicated through the channel

on the right to the right hand side of the disk C³. The piston having moved to the position shown in Figure 4 has closed the passage from the chamber O and the air admitted through the passage P will act against the left hand end of the head C' of the valve forcing the same to the right, opening the auxiliary exhaust port S which communicates with the chamber C⁵ and closing the auxiliary exhaust port R which communicates with the chamber C⁴. These auxiliary ports are controlled by the end heads C² and C' respectively of the valve and contact with the main exhaust in exhausting the air from the main chambers C⁴ and C⁵ as the valve is alternately seated. The greater pressure against the enlarged head C' will overcome the resistance on the head N and assisted by the exhaust of air through the port K, as described in connection with the cycle of operation of Figures 1 and 2 the valve will shift to the opposite position when the first operation described will take place.

What we claim as our invention is:

1. A valve construction for fluid-operated motors comprising a cylindrical casing, bushings therein spaced to form an annular port therebetween, a spool valve having end heads slidably fitting said bushings, and a central head or disk extending into said annular port and alternatively seating upon the opposite ends of said bushings, channels in said bushings surrounding said end heads and having exhaust ports connected thereto, said channels being sealed by said heads respectively when said disk is seated upon the opposite bushing, a fluid supply passage communicating with said annular port, channels in said bushings leading from said supply passage to chambers at the ends of said valve, ports in said valve casing and bushing on opposite sides of said central disk alternatively in communication with said fluid supply passage and leading to the motor controlled by said valve, and an exhaust passage for the chamber at one end of said valve.

2. The combination with a cylinder and a piston therein, of a controlling valve comprising a cylindrical casing, bushings in said casing spaced to form an annular port therebetween communicating with an air supply passage, a spool valve having end heads slidably fitting said bushings, and a central head or disk extending into said annular port and alternatively seated on the opposite ends of said bushings, passages communicating with the annular chambers on opposite sides of said disk and leading respectively to the opposite ends of said cylinder, restricted passages connecting said fluid supply passage with chambers in said casing at opposite ends of said valve, a main exhaust port in said cylinder over-run by said

- piston, a valve exhaust port from the chamber at one end of said piston to said cylinder sealed by said piston when at one end of its stroke, and annular channels surrounding 5 said end heads of the valve provided with auxiliary exhaust ports and respectively communicating with the spaces between said heads and central disk when the latter is seated on the opposite bushing.
- 10 3. The combination with a piston, of a cylinder having a main exhaust port overrun by said piston and valve-controlled supply passages leading to the opposite end of said cylinder, a controlling valve comprising 15 a cylindrical casing having bushings therein spaced to form a central annular port therebetween communicating with the main fluid supply, said bushings having restricted channels therein leading from said main fluid 20 supply to the opposite ends of the valve casing, being also ported on opposite sides of said annular port to communicate respectively with the passages to the opposite ends of said cylinder and being further provided 25 with annular channels in their outer end portions communicating with auxiliary exhaust ports, and a spool valve within said valve casing having end heads slidably fitting said bushings, a central head or disk 30 projecting into said annular port and alternatively seated on the opposite ends of said bushings, said end heads cooperating with said annular channels to alternatively open said auxiliary exhaust in each bushing when 35 the disk is seated thereon.
4. A valve construction for fluid-operated motors comprising a cylindrical casing, bushings in said casing spaced from each other to provide an annular port therebetween communicating with the fluid pressure passage, longitudinal channels in said bushings extending from said fluid pressure passage to opposite ends of the casing and one of said bushings having an outer end 45 portion of smaller diameter, a valve in said
- casing having end heads of different diameters slidably fitting within said bushings, and a valve-controlling exhaust passage communicating with the end of the casing having the head of larger diameter. 50
5. A valve construction for fluid-operated motors comprising a cylindrical casing, bushings therein spaced to form an annular port therebetween, the outer end of one of said bushings being reduced in diameter, a 55 valve in said casing having end heads of different diameters slidably fitting said bushings, a central head or disk projecting into said annular port and alternatively seated on the opposite ends of the bushing, annular 60 channels in said bushings connecting with exhaust ports and controlled respectively by said end head of large diameter and a head or disk adjacent to the head of small diameter, a restricted passage leading from the fluid supply passage to the small diameter end of the valve, a passage from said supply passage to the larger diameter end of the valve, and a valve-controlling exhaust passage for said larger end of the valve. 65
6. A valve construction for a fluid-operated percussive tool comprising a cylindrical valve casing having a central annular port providing opposed valve seats and end chambers differential in size, a valve having 70 differential end heads slidably fitting said chambers and a central head extending into said port for alternately engaging said valve seats, passages conducting live motive fluid to said end chambers whereby the end heads of the valve are continuously subjected to fluid pressure, and a passage extending from the larger of said end chambers under control of the piston of the tool for varying the continuous pressure in said larger chamber. 75
- In testimony whereof we affix our signatures.
